UNITED STATES PATENT OFFICE

RALPH R. BATCHELOR, OF HOLLIS, NEW YORK

MAGNETIC DEVICE

Application filed April 27, 1929. Serial No. 358,732.

My invention relates to improvements in magnetic-devices generally and, while not limited in its application to any special type of magnet, is particularly adapted for use and may be applied with material advantage to the form of electro-magnet now commonly employed in loud speakers of the dynamic type.

In such speakers, the electro-magnet constitutes the principal item of expense, owing to its rather unusual size, the amount of copper and iron employed and the time and labor required in its construction. The pole-pieces of this type of magnet are of such form and so related as to provide a narrow annular gap between them, in which the movable coil, carried by or otherwise secured to the diaphragm of the speaker, is located, free to vibrate clear of the walls of the gap.

In order to bring the pole pieces into the required relation to form the annular gap, it has heretofore been the practice to employ a heavy iron pot-like casing or cylinder suitably proportioned to enclose the magnet core proper and the winding thereon. This cylindrical casing is closed at one end and the closed end is bolted or otherwise secured in centered relation to the core proper.

A removable cover plate is provided for the opposite end of the casing and centrally thereof an opening is formed of a diameter to admit the free projecting end of the core proper and give the necessary clearance for the movable coil.

Ordinarily this cylindrical casing with one end closed, is formed as a heavy casting and both it, and its attached parts,—the core proper and apertured cover plate—must be carefully and accurately machined to provide the required narrow annular gap for the movable coil, which is mounted free to vibrate therein with just sufficient clearance to avoid touching either wall.

Recognizing that the bulk and weight, plus the labor and material costs, are serious disadvantages of the above described structure, I have devised an improved construction in which many of the objectional features are entirely avoided and a considerable saving in cost effected, without loss of efficiency.

In carrying my invention into effect, I first dispense with the heavy cast iron pot-like enclosing casing and substitute for it comparatively light steel stamped up members, two of which, exact duplicates of each other, combine to form the casing and, excepting the necessary punched bolt holes therein, such members, without requiring machine work of any kind, are complete and ready for immediate assembly in a speaker unit, on leaving the stamp press.

As a lighter weight and less costly substitute for the cast, drilled and machined cover plate heretofore employed, I form the same of crossed, twin rectangular plates of comparatively light steel strip and again, excepting the necessary punched bolt holes and central opening therein, these plates are ready for assembly on leaving the stamp press.

A convenient and effective form of mounting or support for the assembled magnet, diaphragm, etc., is found in the use of a stamping, similar in all respects to the above mentioned members I employ as the enclosing casing and to extend one of the poles of the magnet. Thus applied, it serves all requirements without change or modification of any kind.

The accompanying drawings will serve to illustrate a construction suitable for carrying my invention into effect but I do not wish to be understood as limiting myself to the same as various changes may be made therein or other forms employed without departing from the spirit and scope of the invention, as outlined in the appended claims.

In the drawings—

Fig. 1 is a view in elevation, partly in section, of a well known type of dynamic speaker, showing my invention applied;

Fig. 2 is a vertical section on the line s^2-s^2 of Fig. 1;

Fig. 3 is a rear elevation thereof, and

Fig. 4 is a view in perspective showing the assembly of the stamped up members.

Referring now to the drawings, a well-known dynamic type of loud speaker is shown for convenience in illustrating the application of my invention, but it will be under-

stood that other types may be employed, if preferred.

In the speaker shown, a large electro-magnet is employed consisting of a straight cylindrical core 1, carrying a winding 2, so spaced thereon, as to leave the ends or pole-pieces 3 and 4 of the core exposed.

In this type of speaker, the pole pieces of the magnet are brought together in close relation to form an annular gap 5, in which is located the usual movable coil 6, carried by or otherwise suitably connected to a diaphragm 7. The diaphragm is shown mounted in a skeleton metal frame 8, bolted to the 15 magnet casing.

In bringing the pole-pieces of the magnet into relation to form the annular gap, I employ two approximately U-shaped members 9, 9, stamped up from comparatively thin 20 strip steel and arranged one within the other to form in effect a square box, closed at one end and open at the other, the box thus formed being of such size as to completely enclose the magnet core proper and its winding. The members 9, 9, are exact duplicates and, as assembled, to form the box-like casing, are arranged at right angles to each other, as best shown in Fig. 4. At the closed 25 end of the casing, the members are bolted in centered relation, solidly to the core of the magnet, as indicated at 10 and are punched for the insertion of additional bolts 11, 11, which secure the members together.

At the open end of the casing, the ends of 30 the members are bent over forming terminal flanges 12, 12, etc., and bolted to these flanges there is a removable cover formed of crossed twin rectangular plates 13, 13, which are each provided with a central opening 14, of such 35 diameter as to closely encircle the projecting end 4 of the magnet core, leaving only clearance space in the annular gap thus formed between the pole pieces for free movement of the movable coil 6.

As a convenient mounting or support for the electro-magnet, the diaphragm and its carrying frame, I utilize a stamped up member 15, similar in all respects to the stampings employed in forming the box-like casing described and bolt the same to the casing, as indicated at 16, 16, and shown in Figs. 1 and 3.

The U-shaped mounting or support 15, provides ample housing for the transformer 17, 45 which is secured therein by small angle irons and bolts, as indicated at 18, 18.

The circuit connections form no part of the present invention, and it will not, therefore, be necessary to describe the same in 50 detail.

The advantages of the invention will be obvious from the foregoing description. Eliminating the heavy cast iron pot-like casing with its cast cover and the time and labor necessary in machining both to pro-

duce, with required accuracy, the narrow annular gap for the reception of the movable coil, effects a material saving in cost and also in the weight of the structure, as a comparatively light gage steel serves every purpose 70 without loss of function or efficiency. Furthermore, the utilization of one of the stamped members of the casing as a mounting or support results in an additional saving in cost and enables the speaker to be 75 firmly secured in a receiver cabinet in position with the diaphragm paralleling the usual screened opening therein.

In addition to the foregoing, there are various other minor advantages which will 80 be apparent without further comment.

While the present description has been confined to the application of the invention to an electro-magnet, it will be understood that it is equally applicable without material 85 modification, to a permanent type of magnet and may be so used, if desired.

Having thus described my invention, what I claim is:

1. In an electro-magnet comprising a core and a coil wound thereon, means for extending the core to bring the pole-pieces thereof into relation to form an annular gap between them, the said means consisting of a plurality of shaped strip members secured to the core 90 and arranged in nested relation to form an enclosing casing for the magnet winding.

2. In an electro-magnet comprising a core and a coil wound thereon, means for extending the core to bring the pole-pieces thereof 100 into relation to form an annular gap between them, the said means consisting of a plurality of strip members approximately U-shaped, secured to the core and arranged in nested relation, to form an enclosing casing for the 105 magnet winding.

3. In an electro-magnet comprising a core and a coil wound thereon, means for extending the core to bring the pole-pieces thereof 110 into relation to form an annular gap between them, the said means consisting of a plurality of strip members approximately U-shaped, secured to the core and arranged in nested relation, and a plate apertured to encircle the core and combining with the strip members 115 to form an enclosing casing for the magnet winding.

4. In an electro-magnet comprising a core and a coil wound thereon, means for extending the core to bring the pole-pieces thereof 120 into relation to form an annular gap between them, the said means consisting of twin strip members approximately U-shaped secured to the core and arranged at right angles to each other in nested relation, and a plate apertured to encircle the core and combining with the strip members to form an enclosing casing for the magnet winding.

5. In an electro-magnet comprising a core and a coil wound thereon, means for extend-

ing the core to bring the pole-pieces thereof into relation to form an annular gap between them, the said means consisting of twin members suitably shaped and arranged in nested relation at right angles to each other, the ends of the said members being bent over to form flanges, and twin plates apertured to encircle the core and combining with the strip members to form an enclosing casing for the magnet winding.

6. Means for extending the core of an electro-magnet, which consists of twin strip members secured to the core to form a continuation thereof, the said members being approximately U-shaped and arranged at right angles to each other in nested relation to form an enclosing casing around the magnet winding.

7. Means for extending the core of an electro-magnet, which consists of twin strip members secured to the core to form a continuation thereof, the said members being approximately U-shaped and arranged at right angles to each other in nested relation to form an enclosing casing around the magnet winding, and a suitable support for the encased magnet serving as a housing for an additional circuit element.

I affix my signature.

30 RALPH R. BATCHER.
